UNITED STATES PATENT OFFICE

2,009,564

LINER PACK UNIT

Guy Ridge, Bartow, Fla., assignor to Rice, Trew & Rice Co. Inc., Biglerville, Pa., a corporation of Pennsylvania

Application December 26, 1933, Serial No. 704,020

2 Claims. (Cl. 217—3)

This invention relates to a liner pack preformed unit, and it is an object of the invention to provide a unit of this kind which has parts folded in a manner whereby after the unit has been initially placed within a box or kindred container and upon the bottom of the compartment to be filled, certain of the parts can without confusion and delay on the part of the operator be readily extended to overlie the walls of the box or compartment to be packed and in a manner whereby, if desired, portions of the unit may be disposed inwardly across the contents of the box or kindred container before application of the lid.

Another object of the invention is to provide a unit of this kind which is initially folded and initially of a size to be substantially snugly fitted upon the bottom of a box or other container to be filled so that when said unit is opened out the walls of the box or the like will have linings disposed thereover and without requiring any special skill on the part of the operator.

The invention consists in the details of construction and in the combination and arrangement of the several parts of my improved liner pack unit whereby certain important advantages are attained and the device rendered simpler, less expensive and otherwise more convenient and advantageous for use, as will be hereinafter more fully set forth.

The novel features of my invention will herein-after be definitely claimed.

In order that my invention may be the better understood, I will now proceed to describe the same with reference to the accompanying drawings, wherein:—

Figure 1 is a view in perspective of a liner pack unit constructed in accordance with an embodiment of my invention and in its initial folded or compacted form;

Figure 2 is a view in perspective of the unit partially opened out;

Figure 3 is a view in perspective illustrating the unit further opened out;

Figure 4 is a view in perspective of the unit entirely opened out;

Figure 5 is a sectional view taken lengthwise through a conventional type of box with a liner unit constructed in accordance with an embodiment of my invention in initially applied position upon the bottom of the box;

Figure 6 is a transverse sectional view taken through Figure 5;

Figure 7 is a view in perspective showing the

unit fully opened out after being applied to a box;

Figure 8 is a longitudinal sectional view taken through a box showing the unit in complete application before the lid is applied, a second position of certain portions of the unit being diagrammatically indicated by broken lines;

Figure 9 is a transverse sectional view of the assembly as illustrated in Figure 8 with the lid fully applied, a second position of certain portions of the unit being also diagrammatically indicated by broken lines.

Figure 10 is a view in perspective illustrating a unit constructed in accordance with a further embodiment of my invention and opened out.

As disclosed in Figures 1 to 9 of the accompanying drawings, my liner pack unit comprises two sheets A and B of desired dimensions and formed of a paper stock of desired weight or of any other stock that may be employed for the purposes desired. The sheet A may be termed the transverse sheet and B the longitudinal sheet.

In forming the unit the sheets A and B have respectively panels 1 and 2 in superimposed relation and extending at right angles to each other and preferably with the panel 1 of the sheet A lowermost. The side margins of the panel 1 of the sheet A are continued by the side panels 3 and the outer ends of these panels 3 are continued by the flaps 4, one of said flaps 4 being of a length materially greater than the length of the second flap 4.

The end margins of the panel 2 of the sheet B are continued by the end panels 5 and the outer ends of these panels 5 are continued by the flaps 6. The various panels and flaps are preferably separated by folding lines 7.

In the assembly of the unit after the panels 1 and 2 have been superimposed, a panel 3 is swung inwardly and over the panel 2 with its panel 4 swung back over such panel 3. An end panel 5 is then swung inwardly of the superimposed panels 1 and 2 with its flap 6 folded back. The second end panel 5 is then folded inwardly with its end flap 6 disposed in a direction opposite to the flap 6 of the first folded panel 5. Then the second side panel 3 is folded inwardly over the two end panels 5 and their flaps 6 with the flap 4 of the second side panel 3 folded back and extending in a direction opposite to the flap 4 of the first side panel 3. The free outer end portion of the second flap 4 is then folded inwardly to also overlie the panels 1 and 2 as in the complete pack illustrated in Figures 1 and 6.

In the production of the unit the panels 1 and

55

2 are of such dimensions as to substantially snugly engage upon the bottom of a box C or other container with which the unit is to be used while the panels 3 are of such dimensions to substantially conform to the side walls of the box or the like and the panels 5 to conform to the end walls of the box. The flaps 6 and one of the flaps 4 are of desired length but the second flap 4 is of a length to allow the same in making a package to be swung entirely across the upper portion of the box C and tucked down between the first panel 3 and the adjacent side wall of the box or kindred container as is clearly illustrated in Figure 9 of the drawings.

15 After the unit has been initially applied within the box C or kindred container as particularly illustrated in Figures 5 and 6, the uppermost flap 4 is pulled up and outwardly of the box as illustrated in Figures 7 and 9 to bring one of the 20 side panels 3 in proper position against a side wall of the box. The flaps 6 of the end panels 5 are then successively pulled up to bring the panels 5 in proper position against the end walls of the box with said flaps 6 disposed outwardly thereof as is 25 illustrated in Figures 7 and 8 of the drawings.

The second flap 4 is then pulled up to bring the second side panel 3 into proper position against a side wall of the box or the like with said second flap 4 disposed outwardly with respect to the box as is also illustrated in Figures 30 7 and 9. After the box has been filled with the desired content, such as fruit, the flaps 6 are then swung inwardly of the box and over the top of its content and the shorter flap 4 is then swung 35 inwardly and after which the longer flap 4 is drawn across the box with the extremity of said longer flap 4 tucked in between the side panel 3 and the adjacent side of the box C remote from the side panel 3 by which the longer flap 4 is 40 carried.

In view of the foregoing it is believed to be clearly apparent that I have produced a liner pack unit for boxes or kindred containers which 45 can be readily applied without any particular skill on the part of the operator and particularly to assure the proper placing of the lining with dispatch.

In the embodiment of the invention as illustrated in Figure 10, I disclose a unit made from a single sheet of material and which comprises a central panel 1^a of such dimensions to be snugly received upon the bottom of a box or kindred container with the side margins of the panel 1^a continued by the side panels 3^a which are also continued by the flaps 4^a, one of which being of a length to extend entirely across the top of the box and to have its extremity tucked in 10 in the same fashion as has hereinbefore been set forth with respect to the first embodiment of my invention. The end or remaining marginal portions of the panel 1^a are continued by the end panels 5^a which in turn are continued the flaps 15 6^a. This unit is folded after the same fashion as the first embodiment of my invention and is adapted to be extended in the same manner.

From the foregoing description it is thought to be obvious that my invention is susceptible of some change and modification without departing from the principles and spirit thereof and for this reason I do not wish to be understood as limiting myself to the precise arrangement and formation of the several parts herein shown in carrying out 25 my invention in practice except as hereinafter claimed.

I claim:

1. As a new article of manufacture, a pre-formed liner pack unit ready for use comprising 30 two elongated flexible sheets disposed crosswise upon each other with substantially the central portions thereof superimposed, the four resulting flaps of the above assembly constituting side elements of the liner and lying in the pack superimposed upon each other and flat upon the central portions of the elongated members.

2. As a new article of manufacture, a pre-formed liner pack unit ready for use comprising 40 two elongated flexible sheets disposed crosswise upon each other with substantially the central portions thereof superimposed, the four resulting flaps of the above assembly constituting side and cover elements of the liner and lying in the pack superimposed upon each other and flat upon the 45 central portions of the elongated members.

GUY RIDGE.
